UNITED STATES PATENT OFFICE.

EMMETT L. PAGE, OF PONTIAC, MICHIGAN.

MOLDING DEVICE FOR FORMING BEARINGS, &c.

1,321,122.

Specification of Letters Patent. Patented Nov. 11, 1919.

Application filed May 20, 1919. Serial No. 298,520.

To all whom it may concern:

Be it known that J. EMMETT L. PAGE, a citizen of the United States, and resident of Pontiac, Oakland county, State of Michigan, 5 have invented certain new and useful Improvements in Molding Devices for Forming Bearings, &c., of which the following is a specification.

My invention relates to molding devices 10 of the type or class designed to form an element or part thereof from molten metal, and *in situ*, in the position in which it is subsequently to be used; and particularly to a molding device designed to form the comparatively soft bearing metal linings or 15 wearing surfaces within the bearing boxes or seat of a connecting rod or other machine element at which relative rotary motion between two parts of a device is present.

20 The object of my invention is to provide a molding device of the type or class above referred to in which the elements which constitute the same may be readily assembled together with the part or parts which are 25 to receive the molten metal and with which the portion formed from the molten metal is to remain permanently associated, and the several parts referred to held in proper position during the pouring of the molten 30 metal into the mold and until it sets; the molding device as a whole being simple in construction, and so formed and adapted to the finished article produced that the assembling referred to may be readily and quickly 35 accomplished.

A further object of my invention is to provide a molding device of the kind above referred to wherein a relatively large quantity of molten metal is present within an 40 element of the device, and directly above the article or element produced, while the molten metal is setting and cooling, to thereby permit a free escape of occluded gases from the metal as it hardens and to 45 more effectively prevent the formation of blow holes or voids due to other causes within the body of the finished product.

Other objects of invention will appear from the following description thereof and 50 from the concluding claims.

My invention is illustrated in its preferred form in the drawing accompanying and forming a part of this specification; although it will be appreciated that the 55 details thereof may be varied without departing from my invention, and that the same

includes all such variations and modifications of the particular embodiment thereof illustrated as come within the scope of the concluding claims wherein the features in 60 which the invention consists are particularly pointed out.

Referring to the drawing, Figure 1 is a view showing my invention partly in section upon a vertical plane and partly broken 65 away to better show certain of the features thereof;

Fig. 2 is a view showing the mandrel and guides of my invention separate and apart from the mold blocks which form a part 70 thereof;

Fig. 3 is a view showing the under side of the upper mold block;

Fig. 4 is a view partly in plan and partly in section, showing a connecting rod and 75 its cap or bearing secured in place preparatory to forming a bearing therefor, together with clamping means whereby the parts of the rod are held in proper position relative to the mold as a whole; and,

Fig. 5 is a view similar to Fig. 1, but showing the parts before the molten metal has been poured into the mold.

In the drawing, the reference numeral 5 designates a mandrel the form or cross section of which may be varied in accordance with the particular shape of the article or element to be produced, but which is obviously cylindrical in form in case bearings are to be formed at the crank pin end of a 80 connecting rod, or in any other device wherein relative rotary movement between two parts is present and between which parts a bearing of non-friction metal is to be provided.

The upper end of the mandrel 5 is shown as conical in form at 6, and the same is also shown as provided with two oppositely disposed guides 7, 7; said guides being shown as located within grooves extending longitudinally of the mandrel, and as secured in place by transversely extending pins 8, although the details whereby the guides are provided or whereby they are secured to the mandrel are obviously matters of detail, and 95 may be varied. These guides, as will be appreciated from Figs. 4 and 5, serve to space the bearing seat 9 at the end of a connecting rod apart from the cap 10 of the rod to thereby provide spaces between said 100 members within which spacing members or shims are located when the rod is in use in

an engine or other mechanism, and an intervening annular space 11 into which the molten metal is poured, to thereby provide a bearing for the crank pin with which the 6 connecting rod is connected.

The mandrel 5 is provided with two projecting collars 12, 13 located adjacent its lower end and spaced apart from one another to thereby provide an intervening 10 groove 14, and the upper of which collars forms a ledge for supporting the lower of the two mold blocks to be next described; the groove between the collars being provided to facilitate the supporting of the 15 mandrel and mold as a whole in an upright position while molten metal is being poured into the mold, and until the same sets and cools. The mandrel may of course be supported in an upright position in any manner; but in the embodiment of my invention 20 illustrated the same is shown as supported by inserting the lower end thereof between two spaced jaws, one of which is shown at 15, of a suitable support or bracket 16; the 25 sides of the portion of the mandrel within the groove 14 between the collars being flattened, as shown at 17, to thereby prevent the mandrel from rotating about a vertical axis. The entire matter of support for the mandrel, however, and as above stated, is a matter of secondary importance so far as the 30 invention of which this present application relates is concerned, and any scheme for supporting the same in the upright position indicated may be employed.

The reference numeral 18 designates a lower mold block having an opening corresponding in form with the cross section of the mandrel, so that it will fit the same 40 closely, as shown in Figs. 1 and 5, which mold block is supported by the ledge 12 and is provided with oppositely located grooves so positioned as to fit over and receive the guides 7, 7 of the mandrel; the block in 45 question not being secured to the mandrel in any permanent way, but the opening therein being of such a size that it can be easily placed upon the mandrel in the position shown in the drawing, and readily removed 50 from the mandrel in disassembling the parts and removing the rod with the bearing formed therein from the molding device as a whole, after the completion of the formation of the bearing.

55 This mold block is shown as provided with a recess 19 in its upper surface; the purpose of this recess being to permit a flow of molten metal outward and along the sides of the bearings 9, 10 of the connecting rod, 60 to thereby provide a bearing having side wearing faces. This recess or groove will, however, obviously be omitted in case the bearing or other article produced is to terminate in the plane of the upper surface of 65 the mold block in question.

The reference numeral 20 designates a second mold block surrounding the conical upper end 6 of the mandrel, and the under surface of which block rests upon the seats 9 and cap 10 of the connecting rod when the 70 parts are assembled preparatory to the formation of a bearing within the annular space 11 between the said seat and cap. This upper block is held in proper position relative to the mandrel by means of the 75 guides 7, the block having two oppositely located grooves 21, 21 which fit over the said guides and space the block apart from the mandrel. The lower end of the opening of the block through which the mandrel extends is of greater diameter or cross sectional area than the mandrel at the plane of the said lower end, whereby an annular passage is provided between the block and the mandrel through which the molten metal 80 may flow downward and into the space 11 between the mandrel and the bearing seat 9 and cap 10 of the connecting rod. The under side of the block 20 is provided with an annular groove or recess 22 in order to 85 provide a portion of bearing metal extending outward and along the sides of the bearing seat 9 and cap 10, the same as in the case with the recess 19 of the block 18 above referred to.

The guides 7 are provided each with a hole 23 corresponding in position with the holes in the bearing seat 9 and cap 10 of the connecting rod through which the bolts which secure the cap in place extend, and, 90 after the connecting rod and its cap have been put in place resting upon the lower block 18, and the block 20 put in place resting upon the rod and cap, as shown in Fig. 5, the cap and rod are clamped together by 95 means of clamping mechanism best shown in Fig. 4, to thereby hold the parts of the rod together while the molten metal is being poured into the mold to form the bearing and while the same sets and cools. This 100 clamping device is shown as comprising a clamping bar 24 having two hooks 25 pivotally connected at 26 to the free ends of the said clamping bar, and which hooks engage the bearing seat 9 in the manner 105 illustrated in Fig. 4 when the parts of the rod are clamped together, the clamping action being accomplished by means of a screw 27 in threaded engagement with the bar 24, and the inner end of which engages 110 the cap 10, as shown.

In assembling the parts of the rod the bearing 9 and cap 10 are spaced apart from one another by the guides 7 which lie between them when the parts and rod are 112 assembled, as shown in Fig. 4, and the cap and rod are positioned properly relative to one another so as to secure a uniform thickness of metal all about the bearing produced, by means of positioning pins 28 carried by 115

the clamping bar 24 and adapted to extend through the holes in the seat 9 and cap 10 provided for the fastening bolts, and through the holes 23 in the guides 7, to thereby hold the seat and cap in proper position relative to the mandrel and secure a uniform width of the opening 11 about the same and into which the molten metal is poured. Two such pins are shown as employed in the embodiment of my invention illustrated; although it will be appreciated that, so far as concerns the positioning of the parts to secure uniform width of the space 11, such end might be attained by the use of one pin only.

In view of the premises, it will be appreciated that after the parts have been assembled in the position shown, a space corresponding with the bearing to be provided in the seat 9 and cap 10 of the connecting rod will be present between said elements and the mandrel 5, as clearly shown in Fig. 5 of the drawing. Molten metal is then poured into the opening surrounding the mandrel at the upper end of the mold block 20, which metal runs down and into the space 11 which the finished bearing is to occupy. It therefore follows that there is a considerable mass or head of molten metal above the lower surface of the block 20 which lies at the upper end of the bearing while the entire metal thus poured into the mold is still in a fluid condition, the pressure of which metal serves to compact the bearing and to supply molten metal in abundance during the setting and cooling of the metal within the space 11 in which the bearing is formed.

The lower portion of the space surrounding the mandrel within the mold block 20 is in direct communication with the upper ends of the bearing members within the space 11, from which it follows that a free passage is provided through which gases occluded in the molten metal may escape from the bearing and into the riser provided by the molten metal within the mold block 20; thereby more effectively providing for the escape of such gases and insuring the production of a bearing free from blow holes due to such gases, to a shrinkage of the metal within the space 11, or to other causes.

In using my invention the parts thereof, as well as the connecting rod and cap 10, should be at a temperature approaching that of the molten metal at or before the molten metal is actually poured into the mold, in order to prevent a too rapid cooling of the metal and the setting of the same before the mold cavity shall have been completely filled. This heating may obviously be done in any way, and the temperature to which the parts are heated, will obviously vary with the character of the molten metal

to be poured, and will vary also with the form and dimensions of the bearing or other device or element to be produced; the heating of the parts being the more essential in case the thickness of bearing metal to be provided within the bearing seat 9 and cap 10 is slight.

Finally, it will be appreciated that the surplus metal forming the riser within the upper mold block 20 will be severed from the bearing sections within the seat and cap at the end of the connecting rod, after the metal has solidified and cooled and the rod and mold disassembled, and the bearing portions remaining within the seat of the rod and the cap reamed, or otherwise operated upon, to provide a finished bearing.

Having thus described and explained my invention, I claim and desire to secure by Letters Patent:

1. In combination in a molding device of the class described, a cylindrical mandrel; two oppositely located guides extending longitudinally of said mandrel; a block having an opening corresponding in diameter with said mandrel; and a second block having an opening of greater diameter than said mandrel.

2. In combination in a molding device of the class described, a cylindrical mandrel having a ledge adjacent its lower end; two oppositely located guides extending longitudinally of said mandrel; a block having an opening corresponding in diameter with said mandrel, and two oppositely located grooves adapted to receive said guides; and a second block having an opening of greater diameter than said mandrel, and two oppositely located grooves adapted to receive said guides.

3. In combination in a molding device of the class described, a cylindrical mandrel having a conical upper end; and a ledge adjacent its lower end; two oppositely located guides extending longitudinally of said mandrel and the lower ends of which extend below the upper surface of the ledge aforesaid; a block having an opening corresponding in diameter with said mandrel, and two oppositely located grooves adapted to receive said guides; and a second block having an opening of greater diameter than said mandrel and two oppositely located grooves adapted to receive said guides.

4. In combination in a molding device of the class described, a cylindrical mandrel having a ledge adjacent its lower end; two oppositely located guides extending longitudinally of said mandrel and one of which is provided with a hole; a block having an opening corresponding in diameter with said mandrel, and two oppositely located grooves adapted to receive such guides; a second block having an opening of greater diameter than said mandrel, and two oppositely located

- cated grooves adapted to receive said guides; and a clamping device having a positioning pin adapted to extend through the hole aforesaid in said guide.
5. In combination in a molding device of the class described, a cylindrical mandrel having a ledge adjacent its lower end; two oppositely located guides extending longitudinally of said mandrel and one of which is provided with a hole; a block having an opening corresponding in diameter with said mandrel, and two oppositely located grooves adapted to receive such guides; a second block having an opening of greater diameter than said mandrel, and two oppositely located grooves adapted to receive said guides; a clamping bar; a positioning pin carried by said bar and adapted to extend through the hole aforesaid in said guide; two hooks located one at each of the free ends of said clamping bar; and a tightening screw in threaded engagement with said clamping bar and located at the central portion thereof.
25. 6. In combination in a molding device of the class described, a cylindrical mandrel having a ledge adjacent its lower end; two oppositely located guides extending longitudinally of said mandrel and which guides are provided each with a hole; a block having an opening corresponding in diameter with said mandrel, and two oppositely located grooves adapted to receive such guides; a second block having an opening of greater diameter than said mandrel, and two oppositely located grooves adapted to receive said guides; a clamping bar; two positioning pins carried by said bar and which pins are adapted to extend through the holes aforesaid in said guides; two hooks pivotally connected one with each end of said clamping bar; and a tightening screw in threaded engagement with said clamping bar and located at the central portion thereof.
45. 7. In combination in a molding device of the class described, a cylindrical mandrel having two projecting collars adjacent its lower end and spaced apart from one another to thereby provide an intervening groove; two oppositely located guides ex-
- tending longitudinally of said mandrel; a block having an opening corresponding in diameter with said mandrel, and two oppositely located grooves adapted to receive 55 said guides; and a second block having an opening of greater diameter than said mandrel, and two oppositely located grooves adapted to receive said guides.
8. In combination in a molding device 60 of the class described, a cylindrical mandrel having a conical upper end, and two projecting collars adjacent its lower end, and which collars are spaced apart from one another to thereby provide an intervening 65 groove; two oppositely located guides extending longitudinally of said mandrel, and each of which is provided with a hole; a block having an opening corresponding in 70 diameter with said mandrel, and two oppositely located grooves adapted to receive said guides; a second block having an opening of greater diameter than said mandrel, and two oppositely located grooves adapted to receive 75 said guides; and a clamping device having two positioning pins adapted to extend through the holes aforesaid in said guides.
9. In combination in a molding device 80 of the class described, a mandrel; two oppositely located guides extending longitudinally of said mandrel; a block having an opening corresponding in form with the cross section of said mandrel, and two oppositely located grooves adapted to receive 85 said guides; and a second block having two oppositely located grooves adapted to receive said guides.
10. In combination in a molding device 90 of the class described, a mandrel having a ledge at its lower end; a block having an opening corresponding in form with the cross section of said mandrel; a second block spaced apart from said mandrel; and means carried by said mandrel and engaging said 95 second block for thereby maintaining said second block in a definite position relative to said mandrel.
- In testimony whereof I affix my signature.

EMMETT L. PAGE.
